BROODER INSTALLATION

Lynn Otis Selby, Hartford, Conn., assignor to The
Sparmal Engineering Corporation, a corpora-
tion of Connecticut

Application November 9, 1936, Serial No. 109,980

3 Claims. (Cl. 119—32)

My invention relates to brooder installations. It has among its objects to provide an improved brooder installation and, more particularly, such an installation of the type adapted to be heated by products of combustion. A further object of my invention is to provide an improved brooder stove especially adapted to use in connection with a hover and to be heated by an oil burner. A still further object of my invention is to provide such an installation having improved heat circulating means associated with the stove and adapted to cooperate therewith to produce effective and economical heating of the desired area in such manner as to promote the growth of the chicks and eliminate crowding. Another object of my invention is to provide improved air circulating means acting upon the products of combustion rising from the burner and so circulating the same in an improved manner as to produce the above results while delivering the products of combustion outside the brooder house and setting up an improved induced air flow by convection within the hover and toward and from the burner. Still other objects of my invention are to provide improved means for supplying air to the burner, an improved adjustable mounting for the latter, and an improved associated means for leveling the burner base. These and other objects and advantages of my improved construction will, however, hereinafter more fully appear.

In the accompanying drawings I have shown for purposes of illustration one embodiment which my invention may assume in practice.

35 In these drawings—

Figure 1 is a side elevation of a complete brooder installation constructed in accordance with my improvements;

Fig. 1a is a plan view of the structure shown in Fig. 1, part of the hover being broken away and the oil supply being omitted to facilitate illustration;

Fig. 2 is a side elevation of the stove shown in Figure 1 at right angles to the view shown therein, the hover being shown in section;

Fig. 3 is a sectional view on line 3—3 of Figure 1a;

Fig. 4 is a sectional view on line 4—4 of Figure 3, the radially located hover supporting members being shown in full;

Fig. 5 is a sectional view on line 5—5 of Figure 3, and

Fig. 6 is an enlarged sectional view on line 6—6 of Figure 5 with the valve shown in elevation.

55 In the construction shown in Figures 1 to 6, it

will be noted that I have shown a brooder installation including in addition to a hover 1, an improved stove heated by a distillate type oil burner, generally indicated at 2, having the fuel supply thereto from a fuel reservoir 3 controlled by thermostatically controlled valve mechanism, generally indicated at 4, and a metering valve 5; the stove being of an improved construction and including improved circulation means for the products of combustion inducing an improved air flow within the hover, and also having improved leveling means for the burner 2, all as herein-after more fully described.

Before referring to the stove, it will be noted that the burner 2 is of a usual distillate type including a carbon leg 6 and connected by a pipe 7 to the metering valve 5 while the thermostatically controlled valve 4 is disposed between the metering valve and a pipe 8 leading to the fuel supply 3. Here, it will also be understood that the brooder installation including the burner 2, fuel supply 3, and valves 5 and 4, is of the general construction described and claimed in my copending application, Serial No. 336,791, a continuation in part of Serial No. 2,075, that the fuel supply is provided with a vertically adjustable reservoir 9 of usual type, and that my present invention is not concerned with the specific construction of any of these elements.

More particularly considering the stove in which the burner 2 is mounted, it will be noted that herein the carbon leg 6 is suitably connected, as by nuts 10, to the upper horizontal web of an inverted channel member 11, one end of which extends under the burner and is supported under the latter, while the other end of the channel extends laterally from the burner over the supply pipe 7, all as herein-after more specifically brought out in connection with the leveling means. Here, however, it will be noted that a cylindrical member 12 of greater diameter than the burner 2, encloses the latter and is also provided with a closed bottom 13 spaced below the burner base and supported on a pair of legs 14; this bottom 13 being connected by the upper nut 10 to the channel member 11. As shown, the member 12 is also provided with a suitable number of lateral holes 15 just above the bottom 13, four of such holes being illustrated herein, although obviously the number and size of these may be varied as desired to give the proper air flow to the burner. Further, above these holes 15 an inwardly extending annular flange 16 is carried within the member 12 which is spaced below the burner base and is provided with a central open-

ing 17 substantially larger than the carbon leg and through which the carbon leg extends to the burner base. Thus, with the member 12 extending above the burner 2, it will be observed 5 that an air supply is provided for the burner through the holes 15 and up through the enlarged opening 17 surrounding the carbon leg, while the products of combustion will pass upward from the burner in the member 12 into a 10 top section 18 of decreasing cross section and extending through the top of the hover 1, the upper end of the section 18 being covered by a removable cover 19.

In my improved construction, improved means 15 are provided for circulating the products of combustion flowing upward in the member 12. Herein, these means include a sloping baffle 20 of curved cross section, shown in Figure 4, which opens upward through an opening 20' toward 20 the closed portion 18 at the top of the cylindrical member 12. These means further include an annular chamber 21 comprising a horizontal upper annular flange member 22 surrounding the top of the member 12 and a downwardly inclined bottom member 23 likewise extending around the chamber 21, and cooperating therewith to form an annular chamber of triangular cross section extending clear around the upper 25 end of the member 12. Further, it will be noted 30 that an upstanding outlet pipe or stack 24 is connected to the top member 22 and also extends through the hover 1 to the atmosphere, this stack being located adjacent the baffle 20 and a partition 24a also being disposed between 35 the stack 24 and baffle 20. Here also the member 22 is suitably attached to and spaced from the inside of the hover by suitably radially located depending members 25. Thus, it will be evident that the products of combustion rising 40 from the burner 2 in the member 12, will pass up to the cover 19 and be deflected downward and pass out through the opening 20' at the top of the baffle plate 20 and into the annular chamber 21, in which due to the partition 24a, the 45 gases will have to flow completely around the chamber 21, as shown in Figure 4, in order to reach the stack 24.

Cooperating with the means above described 50 for extracting the heat from the products of combustion and distributing the heating effect thereof, is also improved means acting to supply an inner flow of clean heated air within the hover and wholly separate from the flow of the products of combustion. These means include a cylindrical baffle member 26 of greater diameter than the member 12 and enclosing the latter. Herein, this member 26 is imperforate throughout 55 its length and of a length slightly greater than the height of the burner 2, with its lower end extending to a point just above the inlets 15 and its upper end extending to a point slightly below the bottom of the inclined member 23. As shown, this member 26 is also suitably supported 60 in such manner as to permit free air circulation between the same and the member 12, as on the member 12 by one or more radially disposed members 27 of such construction and so spaced as not to obstruct an upward flow of air between the members 12 and 26. As a result of this construction, it will be evident that as air flows into 65 the inlet openings 15 to pass through the enlarged axial opening 17 and to the burner 2, air will also be drawn up inside the baffle 26 and between the same and the member 12, in such manner as 70 to heat this air and also cause a definite circu-

lation of air flowing to the inclined member 23 and over the outer surface thereof and downward along the inside of the hover 1 toward the floor. At the same time, it will be understood that the heat radiated from the member 12 will heat the 5 baffle 26, and that the latter, while its temperature will be somewhat kept down by the flow of air between its inner face and the member 12, will project heat outward around it in such manner as with the radiation from the part 23 and 10 hover 1 to warm the area enclosed within the same.

Assuming that the burner 2 is in operation, it will be evident that the products of combustion passing up through the members 12 and 18 and 15 being deflected downward into and around the chamber 21 in their passage to the outlet 24, as described, the member 23 will be effectively heated. Further, with heated air flowing up through between the baffle 26 and the member 12, it will 20 be evident that this heated air will be deflected laterally and further heated by the member 23 and directed against the inside surface of the cooler hover 1 which in turn will direct it downward close to the floor. Thus, a heated area 25 close to the floor and of substantial width is produced by the stream of circulating air, extending inside and outside the bottom periphery of the hover, while the remainder of the surface within the hover will be heated to a relatively 30 lower temperature as a result of radiation from the baffle member 26, the member 23 and the hover 1. Further, it will be evident that after passing down toward the floor and when just outside the bottom edge of the hover 1, the heated air will tend to rise. Further, it will be understood that fresh air will be supplied to the burner inlets 15 from along the floor which in practice is covered with sawdust or the like.

Referring more particularly to my improved 40 leveling means, it will be noted that the metering valve 5 and thermostatic valve 4 are herein mounted upon a single stand 28 which is in turn provided with a threaded supporting section 29 adapted to be adjustably threaded into the casing of valve 4 and having a supporting foot on its lower end. Further, it will be noted that the upper horizontal web of the channel 11 is suitably clamped by a nut and plate connection 30 to the casing of the metering valve 5. Thus, with the 50 two legs 14 supporting the member 12, by adjusting the stand 28 relative to its threaded support 29 by merely rotating the latter, it will be evident that the burner may be adjusted and leveled, as desired, to bring it into proper working relation; it also being understood that the supplemental reservoir 9 of the oil supply 3 will thereafter be correspondingly vertically adjusted.

In the use of my improved construction, it is 60 found that a relatively wide heated zone or band is provided adjacent the level of the floor and extending outside and inside the bottom periphery of the hover 1, and that the chicks, due to the higher temperature in this band, tend to dispose themselves within its limits, as distinguished 65 from tending to crowd up around the burner base. As a result of the larger heated area thus provided, and the use of controlled circulation of relatively warmer air therein and cooler air surrounding the burner base, it is thus made possible to make the chicks prefer the materially larger and therefore safer, yet warmer area around the periphery of the hover which is heated by a moving stream of fresh air, and thereby 70 not only eliminate losses due to crowding and 75

suffocation, but also produce more healthy and vigorous chicks, while permitting the chickens to run freely across the area beneath the hover without danger of burning. Attention is further directed to the fact that my improved construction is such as to extract a substantially increased amount of heat from the products of combustion while obtaining the results hereinabove described, the annular flow of heated gases being such as to transmit a substantial proportion of the heat to the inclined member 23, while the heated air in the area above the member 22 also tends to be drawn out by the flow of air down the inside of the hover 1. Further, the annular flow described results in more even heating of the surface 23 irrespective of variations in temperature. Thus, even if one wall of the brooder house is colder than another, the member 23 and hover will still be uniformly heated. The construction is also such as to avoid overheating of any part with which the chicks or the attendant are apt to come in contact, while it will also be evident that due to the control of the products of combustion and the means provided for lowering the temperature thereof through the circulation described, any danger of fire is minimized. Attention is also directed to the facility with which the construction may be assembled and cleaned, and to the fact that if desired burners of different size may readily be substituted. Also, it will be noted that the construction is such as to permit the manufacture of the complete installation, including the hover, at relatively small expense. These and other advantages of my improved construction will, however, be clearly apparent to those skilled in the art.

No claim is made herein to the oil burner and its mounting, casing, leveling, and oil and air supply means, this subject matter being claimed 40 in a divisional application, No. 365,316, filed November 12, 1940.

While I have in this application specifically described one form which my invention may assume in practice, it will be understood that the 45 same may be modified and embodied in various other forms without departing from its spirit or the scope of the appended claims.

What I claim as new and desire to secure by Letters Patent is:

50 1. In a heater installation, a heater enclosing casing forming a vertically elongated chamber, a heater in the lower end of said chamber delivering products of combustion upwardly therein and having air inlet means at the lower end 55 of said chamber, annular chamber forming means surrounding said casing intermediate its ends receiving products of combustion therefrom through a lateral aperture in one side of said casing and discharging the same to the atmosphere at a peripherally spaced point, inwardly and upwardly inclined baffle means extending upward from the inner wall of said casing below said aperture and cooperating with said chamber walls for deflecting and directing the rising products of combustion from said heater upwardly along the opposite side wall of said casing above said annular chamber and downwardly along said apertured wall, and deflecting said downwardly directed stream into said annular chamber, and a heat directing member carried by the upper end of said casing having downwardly and outwardly directed side walls en-

closing said casing and directing rising heated air downwardly into the air stream flowing toward said inlet means.

2. In a heater installation, a generally cylindrical heater enclosing casing forming a vertically elongated chamber closed at the top and having lateral air inlet openings adjacent the bottom thereof, a heater axially located in the lower end of said chamber above said bottom air inlet openings having side walls spaced from the side walls of said casing and having vertical air passages extending through said heater and delivering products of combustion upwardly into the top of said chamber, a plate in said casing beneath said heater and above said air inlet openings having a central opening directing the air from said inlet openings axially into said chamber beneath said heater, annular chamber forming means surrounding said casing intermediate its ends receiving products of combustion therefrom through a lateral aperture in one side of said casing and discharging the same to the atmosphere at a peripherally spaced point, baffle means on the wall of said casing adjacent said aperture directing the rising products of combustion from said heater to flow upwardly along the opposite side wall of said casing and directing said products of combustion into said annular chamber as they flow downwardly along said apertured side wall, and an annular heat 30 directing member carried by the upper end of said casing having a downwardly and outwardly directed bottom portion surrounding said annular chamber and directing the stream of air flowing upwardly along the heated surfaces of said casing and annular chamber downwardly into the air stream flowing toward said inlet openings. 35

3. In a heater installation, a generally cylindrical heater enclosing casing forming a vertically elongated chamber closed at the top and 40 having lateral air inlet openings adjacent the bottom thereof, a heater in the lower end of said chamber above said bottom air inlet openings delivering products of combustion upwardly into the top of said chamber, annular chamber forming means surrounding said casing intermediate its ends receiving products of combustion therefrom through a lateral aperture in one side of said casing and discharging the same to the atmosphere at a peripherally spaced point, said annular 45 chamber forming means including an upwardly and outwardly directed external heating surface, baffle means on the wall of said casing adjacent said aperture for deflecting the rising products of combustion from the heater upwardly along the opposite side walls of the casing and intercepting and directing the downwardly flowing stream into said annular chamber, an annular collar surrounding and spaced from the lower end of said casing having an annular open lower end adjacent said air inlet openings and an annular open upper end discharging rising air onto the upwardly and outwardly directed heated surface of said annular chamber forming means, and a heat directing member carried by the upper end of said casing having a downwardly and outwardly directed bottom portion surrounding said annular chamber forming means and directing downwardly the heated air rising along said upwardly and outwardly directed surface 50 55 60 65 70 thereof.

LYNN OTIS SELBY.
